Russell Bond
ATTORNEY

UNITED STATES PATENT OFFICE.

LEO BAUM, OF BROOKLYN, NEW YORK; ALEXANDER RUSSELL BOND EXECUTOR OF
SAID LEO BAUM, DECEASED.

PICTURE MOUNTING FOR JEWELRY.

Application filed July 23, 1927. Serial No. 207,936.

My invention relates to improvements in mountings for pictures or flat ornaments and particularly to mountings adapted for use in lockets and other jewelry.

5 Heretofore it has been the custom to provide lockets with bezels upon which open frames are secured. A picture is inserted within the bezel and is held in place by the frame which is clamped down on the bezel 10 and overlaps the margins of the picture. This means of fastening applies not only to lockets but to all sorts of jewelry in which it is desired to mount a picture or a flat ornament.

15 It is an object of my invention to provide an improved means of securing a picture or flat ornament in any piece of jewelry, whether the jewelry be in the form of a locket or in some other form. To this end my invention provides a mounting which may, at will, be 20 dismounted without the use of tools.

Another object of my invention is to provide a frame in which pictures or flat ornaments may be easily inserted and removed.

Another object is to provide a frame which 25 will be securely held in its mounting and which is formed with means by which it may be readily withdrawn from its mounting.

30 My invention is particularly adapted for use with locket rings, that is, rings formed with a recessed head constituting a locket body and with a lid for closing the recess. However, my invention is not limited to such application but obviously can be applied to other forms of jewelry as well.

35 Another object of my invention is to provide a mounting of the character described above which is very simple in construction and which may be manufactured at low cost.

40 With these and other objects in view which will appear hereinafter, my invention consists in certain novel features of construction and combinations of parts which will be described in connection with the accompanying drawings illustrating a preferred 45 embodiment of my invention, and the novelty and scope of my invention will be clearly defined in the appended claims.

In the drawings,

50 Fig. 1 is a plan view of a locket ring with the lid of the locket partly open to show my improved frame secured in the locket body;

Fig. 2 is a side elevation of a locket ring partly broken away to show the frame mounted in the locket body; and

Fig. 3 is a view of my improved frame and 55 a picture to be secured therein, the various parts being shown separated.

I have chosen for illustration a ring of the type disclosed in my co-pending application, Serial No. 205175, filed July 12, 1927. 60 The details of the locket, however, form no part of the present invention except as the locket provides a suitable seat or mounting for my improved frame. Obviously the locket could be of circular, oval or any other 65 form.

Referring to Figs. 1 and 2 it will be observed that the ring 10 is formed with a head 11 in which there is a recess 12. The recess may be closed by a lid 13 which has sliding 70 engagement with the head 11. In making locket rings it is usually more convenient to taper the side walls of the locket body so that the recess 12 is somewhat narrower and shorter at the bottom than at the top. Owing 75 to this taper it is not practicable to depend upon friction to hold a frame in the bottom of the recess. Therefore I provide the recess with a pair of shallow grooves or sockets 14 formed in opposite walls thereof and located close to the bottom of the recess. These 80 grooves are adapted to cooperate with means on the frame to hold the frame in place at the bottom of the recess, as will be explained presently.

85 The picture frame is formed preferably of two parts 15 and 16. The part 16 is in the form of a flat plate while the part 15 is in the form of an open frame preferably of metal and provided at one side edge with a laterally projecting lug 17 formed integrally with the frame member. At the opposite side edge of the frame member there is a latch also formed integrally with the frame member and consisting of a tab bent back 90 upon itself to form a laterally projecting lug 18 and then turned upward and outward as shown at 19 to provide means for operating the latch. At each end the member 15 is bent under as shown at 21—21 to provide guides 95 in which the plate 16 may slide laterally.

100 The parts shown in Fig. 3 are assembled as follows: A picture 22 is laid on the plate 16, and then the picture and plate are slid laterally into the member 15. If desired 105 a thin film of transparent material such as isinglass or celluloid may also be placed on the plate 16 over the picture 22 before slid-

ing the parts into the frame member 15. The picture thus mounted is then inserted in the recess 12 with the lug 17 entering one of the sockets 14. A slight pressure on the 5 frame will then cause the lug 18 to snap into engagement with the opposite groove 14, thus holding the frame and picture snugly in the locket.

It will be understood that there is sufficient spring in the parts to permit the lug 10 18 to snap into the groove 14 and prevent the frame from falling out of the locket. Whenever it is desired to remove the picture from the locket, this can be done very readily 15 without the use of tools by simply inserting the thumb nail under the part 19 of the latch and springing the lug 18 out of its socket. The frame can then be taken apart and another picture substituted for the one already 20 therein if so desired.

Obviously the plate 16 and the frame member 15 with its latch and lug 17 may be stamped out of a sheet of flat metal, after 25 which the member 15 is bent to the form shown in Fig. 3. The parts can thus be made at a very low cost.

If desired the plate 16 may be omitted altogether and merely the frame part 15 used. However, I prefer to employ a plate 16 as 30 a backing for the picture, particularly if the picture is printed on thin paper, so as to keep the picture smooth. Instead of applying the lug 17 and the latch to the frame member 15 they could also be applied to the 35 plate 16, and, therefore, I do not wish to limit myself to the particular construction shown in the drawings. Obviously various other changes could be made in the form and construction of my improved frame and in 40 arrangements of various parts, without departing from the spirit and scope of my invention as defined in the claims.

By the term "picture" as used in the appended claims, I mean to include any flat 45 device, engraved plate, or ornament, such as might be mounted in a piece of jewelry.

Having thus described my invention what I claim and desire to secure by Letters Patent, is:

50 1. A picture frame for use in jewelry, comprising a frame member centrally apertured to expose a picture, said member being formed with undeturned ends to provide guides in which a picture may slide 55 and being further formed with a lug at one

side and a latch at the other side adapted for securing the frame member to a base.

2. A picture frame for use in jewelry, comprising a plate member and a frame member, the latter being formed with undeturned ends to provide guides in which the plate member may slide, and one of said members being formed with a lug at one 60 side and a latch at the opposite side thereof.

3. A picture frame for use in jewelry, comprising a plate member and a frame member, the latter being formed with undeturned ends in which the plate member may slide, and the frame member being formed with a lug projecting from one edge thereof and with a latch at the opposite edge thereof. 65

4. A picture frame for jewelry comprising two stampings of sheet metal, one of the stampings being in the form of a frame with opposite ends turned under to form guides, the other member being in the form of a plate adapted to engage and slide in said guides, the frame member being also formed at one side with a laterally projecting lug and at the opposite side with a tab bent back 70 on itself to form a laterally projecting lug, the tab having an upwardly bent finger portion. 75

5. A picture mounting of the character described, comprising a base formed with a 85 recess and with sockets in opposite walls of the recess, a picture frame adapted to be seated in the recess, a lug at one edge of the frame adapted to enter one of the sockets, and a spring latch at the opposite edge of 90 the frame adapted to engage the other socket, the latch being formed with a finger piece for withdrawing the latch from its socket.

6. A picture mounting of the character 95 described comprising a base formed with a recess and with sockets in opposite walls of the recess, a picture frame adapted to be seated in the recess, a lug at one edge of the frame adapted to enter one of the sockets, and a spring latch, the latter comprising a 100 tab bent back on itself to form a lug adapted to enter the other of the sockets, the free end of the tab being bent upwardly and toward the adjacent wall of the recess to form a 105 finger piece.

Signed at New York, in the county of New York and State of New York this 16th day of July A. D. 1927.

LEO BAUM.
